COMBINED SALT SHAKER, PEPPER SHAKER, AND STAND THEREFOR

Benjamin W. Price, 8131 Atlantic Blvd.,
Jacksonville, Fla. 32216

Filed Aug. 22, 1974, Ser. No. 499,444

Term of patent 14 years

Int. Cl. D7—06

U.S. CL. D7—55

Fig. 1

Fig. 2

Fig. 3

Fig. 4

Fig. 5

Fig. 6

FIG. 1 is a top front perspective view of a combined salt shaker, pepper shaker and stand therefor showing my new design;

FIG. 2 is a front elevational view thereof;

FIG. 3 is a rear elevational view thereof;

FIG. 4 is a right side elevational view of FIG. 3;

FIG. 5 is a left side elevational view of FIG. 3; and

FIG. 6 is a top plan view thereof.

I claim:

The ornamental design for a combined salt shaker, pepper shaker, and stand therefor, as shown.
